[57] CLAIM

The ornamental design for a chair for use primarily on a boat, as shown and described.

DESCRIPTION

FIG. 1 is a front elevational view of a chair for use primarily on a boat showing my new design;
FIG. 2 is a rear elevational view;
FIG. 3 is a top plan view;
FIG. 4 is a bottom plan view;
FIG. 5 is a side elevational view, the opposite side being a mirror image thereof; and
FIG. 6 is a perspective view of the chair on an enlarged scale.

FIG. 1

FIG. 2

FIG. 3

FIG. 4

FIG. 5

FIG. 6
